DUAL CARBURETOR

David E. Anderson, Shaker Heights, Ohio, assignor to Thompson Products, Inc., Cleveland, Ohio, a corporation of Ohio

Application October 27, 1948, Serial No. 56,793

6 Claims. (Cl. 261—18)

1

The present invention relates to a dual carburetor and more particularly to a unitary carburetor for the feeding of both main fuel and supplemental fuel to an internal combustion engine in metered amounts and for forming a main fuel-air mixture containing added supplementary fuel in amounts correlated with the operating conditions of the engine and sufficient to prevent engine pre-ignition and detonation.

The desirability of employing supplementary fuel or fuel additives with the main hydrocarbon-air mixture ignited within the combustion chambers of an internal combustion engine has been recognized. In the prior art the improvement of the main fuel has in general been accomplished in two ways. First, additives, such as tetraethyl lead, organic halogen compound and the like, have been added directly to the fuel for solution therein and subsequent injection to the main fuel-air stream at all times during operation of the engine. Second, various types of devices for injecting supplementary fuel in accordance with the manifold vacuum of the engine have been proposed. These devices are typically mounted on the engine independently of the carburetor and are vented directly to the manifold vacuum of the engine for the introduction of supplementary fuel in accordance therewith. Such devices are an added expense since they are provided independently of the main fuel injection system, are generally inefficient since supplementary fuel is not injected in strict accordance with engine requirements, and further make no provision for the introduction of additional supplemental fuel on the sudden acceleration of the engine. Further, in such devices the supplementary fuel flow rate remains constant under all engine operating conditions at which any supplementary fuel flow occurs.

Engine operating conditions, when measured in terms of intake manifold vacuum, may be divided into three general ranges. When the engine is operating at high vacuums (100 inches water vacuum and higher), engine knock and pre-ignition do not occur, while operation at low vacuums (from about 0 to 70 inches water vacuum) is very conducive to rough engine performance, knock and pre-ignition in the absence of anti-knock additives. In the intermediate range of operation (from about 70 to 100 inches water vacuum), the engine knock may occur in the absence of supplementary fuels or anti-knock additives, although lesser amounts are required than at the lower vacuums. Upon sudden acceleration or operation at high speed and high load, the engine

2

functions at low vacuums and supplementary fuel is primarily required at these vacuums. However, supplementary fuel is also required during operation at intermediate vacuums, although in lesser quantities.

The present invention now provides a fuel carburetor for the feeding of both supplementary fuel and main fuel through separate injection systems into a common air intake venturi. Such a device is more compact, provides means whereby additional supplemental fuel may be introduced by means of an accelerating pump, together with main fuel upon sudden acceleration of the engine, and also provides for the close correlation of fuel feeding with the engine performance throughout the entire range of engine operating conditions, with supplementary fuel feeding occurring during intermediate engine vacuums and additional feeding at low vacuums.

The device of the present invention comprises generally a single casing provided with an air inlet conduit carrying spaced choke and throttle valves and a venturi mounted therebetween. The casing defines separate fuel float chambers connected to a source of main fuel and supplementary fuel respectively and communicating with separate injection jets connecting the flow chambers with the air intake venturi. Each of the flow chambers is provided with diaphragm controlled valve means for regulating the flow of fuel therefrom in accordance with the intake manifold pressure of the engine. Each of the chambers is also provided with a separate accelerating pump connected to a common nozzle for injecting a mixture of main fuel and supplementary fuel to the air intake venturi upon the rapid acceleration of the engine caused by the sudden depression of the engine throttle control. Thus, an additional mixture of supplementary fuel and main fuel is fed to the engine during periods of rapid acceleration to prevent preignition and detonation. The present invention also provides positive mechanical means directly linked to the throttle control element for shutting off the flow of supplemental fuel during those periods of operation at which the engine is operating at full throttle and high vacuum such as occurs at high speed.

The present invention thus provides a dual carburetor for the feeding of a main fuel-air mixture to the engine and the addition of supplementary fuel to this mixture in amount directly proportional to the operating characteristics of the engine. Means are provided for feeding supplementary fuel under medium man-

ifold vacuum conditions, for feeding additional supplementary fuel under extremely low manifold vacuums, for feeding additional supplementary fuel during rapid acceleration of the engine, and for interrupting flow of supplementary fuel by mechanical means during those periods in which the engine is operating at full throttle and high speed.

It is, therefore, an important object of the present invention to provide a unitary carburetor which meters fuel and air to an engine in intermixed relation with varying amounts of anti-detonant fluid being added to the main fuel-air mixture in amounts controlled by the intake manifold pressure and also if desired by the throttle opening movement.

Another important object of the present invention is to provide a dual carburetor for the feeding of main fuel and supplementary fuel to the intake manifold of an internal combustion engine, the carburetor having separate injection systems for each type of fuel and providing a main fuel-air mixture including metered amounts of supplementary fuel, the amount of supplementary fuel depending upon the operating conditions of the engine.

A further object of the present invention is to provide means for adding supplementary fuel to a main fuel-air mixture fed to an internal combustion engine in accordance with the intake manifold vacuum to prevent pre-ignition and detonation and also means operating independently of manifold vacuum to provide an extra supplementary fuel charge when the throttle is suddenly opened and means linked mechanically to the throttle actuating mechanism for cutting off the flow of supplementary fuel when the engine is operating at full throttle and high speed.

A still further object of the present invention is to provide a dual carburetor for feeding main fuel and supplementary fuel to the intake manifold of an internal combustion engine, the carburetor having separate injection systems for each type of fuel, one of said systems feeding main fuel-air mixture in amounts correlated to the manipulation of the throttle valve and to the engine intake manifold vacuum and the other system feeding supplementary fuel for admixture with the main fuel-air mixture in amounts sufficient to prevent engine pre-ignition and detonation, the amount of supplementary fuel being correlated with the manifold vacuum and the movement of the throttle valve to feed supplementary fuel to the engine in accordance with engine operating conditions, to provide an added supplemental fuel charge upon sudden opening movement of the throttle valve, and to interrupt the flow of supplementary fuel when the engine is operating at full throttle and high speed.

A yet further object of the present invention is to provide a method of preventing pre-ignition and detonation in internal combustion engines by feeding supplementary fuel to the main fuel-air mixture introduced into the engine in accordance with the engine intake manifold vacuum, supplying extra supplementary fuel charge in accordance with movement of the throttle valve when the valve is suddenly opened, and interrupting the flow of supplementary fuel when the engine is operating at full throttle and high speed, and also when engine is operating at part throttle at a medium high speed where the engine does not detonate.

Other and further important objects of this

invention will be apparent from the disclosures in the specification and the accompanying claims.

Figure 8 is a schematic view of the entire dual carburetor of the present invention.

As shown on the drawings:

In Figure 1, reference numeral 10 refers generally to a dual carburetor of the present invention comprising generally a housing enclosing separate main fuel injection and supplementary fuel injection systems which cooperate for the feeding of main fuel and supplementary fuel to the engine to which the carburetor is attached in accordance with the operating conditions of the engine. Each of these systems will herein-after be described in detail.

Casing and engine controls

As shown in Figures 1, 2 and 4, the casing enclosing the operating parts of the dual carburetor of the present invention comprises an upper casing section 11, an intermediate casing section 12 and a lower casing section 13. The upper section 11 is provided with a generally cylindrical, upstanding central boss 14 provided with a central, open-ended aperture 15 defining the air inlet of the carburetor. The passage of air through the inlet 15 is controlled by a choke valve 16 mounted in the inlet on a pin 17 extending thereacross. Movement of the choke valve 16 on the pin 17 is controlled by a choke lever 18 pivoted to the upper casing section 11 on pin 18a and connected to the engine choke control through knob 18b.

Upper casing section 11 also carries a pair of upstanding port housings 19 and 20 connected to a suitable source of supplementary fuel and main fuel respectively. The upper casing section 11 is secured to the intermediate casing section 12 by suitable means, such as by screws 21 threadedly retained by bosses formed integrally with section 12.

The intermediate casing 12, as best shown in Figure 1, defines a pair of open topped float chambers 22 and 23 adapted to contain supplementary fuel and main fuel respectively. The chambers 22 and 23 are separated by a generally cylindrical, central boss 24 having an axially extending open ended aperture 25 extending therethrough. Boss 24 carries a venturi 26 mounted centrally thereof by means of supporting bosses 27.

The intermediate section 12 of the casing also carries a pair of upstanding exterior bosses 28 and 29 in communication with the flow chambers 22 and 23 respectively, as at 28a and 29a (Fig-

ure 4), and adapted to receive accelerating pumps as hereinafter described.

The upper casing section 11 carries bosses 30 and 31 closed at their upper ends and adapted to register with the bosses 28 and 29 for closing the same to form the complete accelerating pump housing, as best shown in Figure 5.

The lower casing section 13 is secured to the intermediate casing section 12 by means of screws 32 (Figures 2 and 3) threadedly retained by the intermediate section, the lower casing section being formed with flange 33 adapted for securing the complete carburetor 10 to the intake manifold of an internal combustion engine. The lower casing section 13 is provided with an intermediate, generally cylindrical boss 34 carrying a throttle valve 35 (Figure 3) mounted on pin 36 pivotally carried by the boss 34. Pin 36 carries a throttle lever 37 having a depending knob 37a adapted to be connected to the throttle control rod or cable (not shown) of the engine. Throttle lever 37 is connected to links 38 and 38a (Figures 1 and 3) to accelerating pump actuating arm 39 for the main fuel accelerating pump housed in the casing defined by the sections 29 and 31, the throttle lever also being connected through link 38b (Figures 2 and 5) to accelerating pump actuating arm 40 by the supplementary fuel accelerating pump housed in housing sections 28 and 30. Boss 34 also carries an idling needle valve 41 for controlling the admission of main fuel to the intake manifold during idling of the engine as hereinafter described.

Main fuel injection system

The main fuel injection system of the carburetor of the present invention is illustrated in Figures 3, 5 and 7 of the drawings, and comprises generally main fuel float chamber 23 (Figures 3 and 4) in which a float 42 is pivotally mounted on a pin 43 carried by the chamber wall. Fuel is introduced into the float chamber 23 through main fuel inlet port 44 located in inlet port housing 20, main fuel flowing through an orifice 45 formed in an orifice sleeve 46 threadedly retained within the housing 20. Admission of fuel to the orifice 45 is controlled by a needle valve 47 guided by sleeve 46, movement of the valve 47 being controlled by the float 42 through float supporting arm 48. Float chamber 23 is vented to atmospheric pressure through vent tube 49 extending into the air intake 15 (Figures 1 and 3). Tube 49 communicates with an air chamber indicated at 50 connected by passages 51 and 52 to the flow chamber 23. Port 53a in the walls of chamber 50 insures that the supply of air introduced through conduit 49 remains at atmospheric pressure despite possible pressure built up by the sudden rush of air into the air inlet 15.

The high speed main fuel injection system comprises generally a main jet 53 and means for feeding fuel and air to the jet 53. Jet 53 extends from flow chamber 23 to venturi 26 and comprises generally a boss 54 bored as at 55 and apertured as at 56 to connect chamber 23 with venturi 26, the bore 55 being threaded as at 55a. Tube 57 having a reduced diameter central portion is mounted within the bore 55 and extends axially therethrough into the venturi 26 adjacent the throat thereof. The tube 57 is apertured as at 58 and adjacent its tip 57a at 58a. A block 59 extends radially across the lower portion of the tube 57, and a nipple 60, having an axially extending orifice 61 and exterior threads, is retained in the threaded end of bore 55. Air is

bled into jet 55 through air chamber 62 defined by dome housing 63 adjacent the mouth of venturi 26 and connected to an annular space between tube 57 and bore 55 and in communication with the aperture 58a through tubes 64.

During high speed operation of the engine, air flowing through venturi 26 will draw main fuel from the flow chamber 23 through jet 53 into the venturi for admixture with the air flowing therethrough and subsequent introduction into the engine.

It has been found that the vacuum within the intake manifold of an internal combustion engine decreases during those periods of operation of the engine which are particularly conducive to pre-detonation and knock. The carburetor of the present invention feeds main fuel into the intake manifold of the engine in larger amounts during those periods of operation most conducive to knocks by means of a diaphragm controlled valve 65 located in float chamber 23, as illustrated in Figures 4 and 7 of the drawings. Valve 65 is mounted in a boss 66 extending upwardly into float chamber 23 and downwardly into vacuum chamber 67 defined by adjacent recessed portions of intermediate casing section 12 and lower casing section 13. Vacuum chamber 67 is vented to intake vacuum through port 68, conduit 69 (Figure 4) and port 70 (Figure 3) communicating with the interior aperture of casing section 13 below throttle valve 35.

An open-ended sleeve 71 having an axial bore 71a is threadedly retained in the boss 66 and carries a flexible diaphragm 72 closing its open, flared lower extremity 71b. Valve 65 is provided with a threaded upper shank 65a extending above sleeve 71, an intermediate conical seating face 65b and a reduced shank 65c extending through a restricted orifice 73 formed in the upper portion of the sleeve 71, and the seating face 65b is adapted to close the orifice 73. Valve 65 is secured to diaphragm 72 by washers mounted on either side of the diaphragm. A bonnet 74 is threadedly retained on the upper portion 65a of the valve 65 and a spring 75 extends between the sleeve 71 and bonnet 74 to urge the conical seating face 65b away from the orifice 73.

Outlet ports 76 provide an exit for main fuel flowing from float chamber 23 through the orifice 73 into the interior of sleeve 71. A passage 77 provides egress for fluid from chamber 23 to main metering jet 53. A block 78 having a restricted orifice is mounted in the passage 77 for metering the fluid flowing therethrough.

The operation of valve 65 to meter fuel to the conduit 71 in accordance with the intake manifold vacuum of the engine will be readily appreciated. During operation of the engine at low or constant speed, the intake vacuum vented to the chamber 67 will be sufficient to draw the diaphragm 72 downwardly against the action of the spring 75 to seat the conical seating face 65b of the valve 65 against sleeve 71, closing the orifice 73. However, during periods of rapid acceleration, high speed, or high load, the vacuum within the chamber 67 will be reduced, the spring 75 will be able to overcome the resistance of diaphragm 72, and the spring 75 will unseat the valve 65 establishing the flow of fuel from the float chamber 23 through orifice 73, ports 76, and passage 77 into the main fuel jet 53.

As shown in Figures 3 and 7, fuel is introduced into idling jet 79 through upwardly extending passage 80 formed in boss 24 and connected to lateral passage 81 communicating with down-

wardly extending passage 82 connected with passage 77 leading from float chamber 23 to main jet 53. When throttle valve 35 is closed, and engine inoperative, valve 65 is open since atmospheric pressure exists in chamber 67 and fuel stands in passage 77 and jet 53 at the level of fuel in float chamber 23. Tube 83 mounted in passage 82 extends into proximity with block 78 and the suction, generated by the use of the engine starter with the throttle valve closed, will be sufficient to draw fuel through passages 81 and 80 to jet 79 and, following the first starting of the engine, a siphoning action will cause fuel flow to continue. Air flowing through vent 83a (Figure 3) and passage 84 will be bled into the fuel stream passing through passage 80. Following the opening of throttle valve 35, fuel and air will also be admitted into the fuel intake through idling jet 85.

At intermediate throttle openings (between idling and full power) the vacuum in 67 will be high enough to keep valve 65 closed. The fuel then flows from 23 through 56 and then through 61 into jet 53 where the fuel is mixed with air flowing through 51a and thence into throat of venturi 26.

When the engine is undergoing rapid acceleration, usually caused by rapid opening of throttle valve 35, an extra charge of main fuel will be required, and this extra fuel charge may suitably be supplied by means of accelerating pump 86 illustrated in Figure 5 of the drawings. Pump 86 is positioned within the housing 29 and 31 formed integrally with casing sections 12 and 11, respectively, as hereinbefore described. Pump 86 comprises generally pump actuating arm 39 linked through throttle links 38 and 38a to the throttle lever 37 (Figure 2). The pump actuating arm 39 carries at its lower end a sleeve 87 slideable on the arm and provided with a depending, generally annular gasket 88 contacting the interior curved surfaces of housing 29. A coil spring 89 is retained on sleeve 87 to urge the gasket 88 outwardly against the walls of the housing 29.

An annular flange 91 is secured to the arm 39 intermediate the ends thereof and a coil spring 92 is compressed between the flange 91 and the sleeve 87. Since the sleeve 87 is slidably fitted on the arm 39, the spring 92 provides a resilient support for the entire sleeve 87 by permitting sliding movement of the sleeve relative to the arm. A second coil spring 93 is compressed between the upper interior surface of the housing 31 and the flange 91, this spring urging the entire assembly consisting of the arm 39 and the sleeve 87 downwardly within its housing.

Communication between the accelerating pump 86 and the interior of the float chamber 23 is established through a ball check valve controlled conduit 94 connecting the chamber and the housing as best shown in Figure 4. Egress from the pump housing is provided through conduit 95 extending upwardly through one wall of the boss 24, as shown in Figure 4, the conduit leading into nozzle 96 (Figure 1) located in the air inlet 15 in a position adjacent the upper extremity of venturi 26.

The operation of the pump 86 will be readily understood since upon upward movement of the actuating arm 39 main fuel is drawn from the float chamber 23 into the interior of the pump casing through the conduit 94, and upon downward movement of the actuating arm 39, as upon suddenly opening the throttle valve 35 as by

means of the throttle lever 37, main fuel is forced from the housing through conduit 95 into the nozzle 96 the main fuel being introduced into the venturi through the nozzle 96.

Supplementary fuel injection system

Supplementary fuel is injected through the dual carburetor of the present invention in a manner analogous to that hereinbefore described in connection with the main fuel charge introduced into the intake manifold of the engine. Supplementary fuel is injected under conditions of low vacuum at which pre-ignition and detonation are likely to occur in the absence of such feeding. The supplementary fuel injection system for feeding under low vacuum condition is illustrated in Figures 3, 4 and 6 of the drawings.

As particularly shown in Figure 3 of the drawings, supplementary fuel is fed from a suitable source through inlet 97 located in inlet housing 19 and orifice 98 controlled by needle valve 99, the valve being actuated by float 100 pivoted to the casing at 101, as hereinbefore described in connection with float 42 in chamber 23. Float chamber 22 is vented to air through passage 102 connected to passage 51. Fuel is fed through jet 103 in accordance with the manifold vacuum of the engine upon which the carburetor is mounted through diaphragm controlled spring urged valves 104 and 105 located in fluid chamber 22 and shown in Figures 4 and 6.

Valves 104 and 105 are similar in construction and operation to the valve 65 illustrated in Figure 7 and hereinbefore described. For example, valves 104 and 105 are mounted on a pair of bosses 106 and 107, respectively, provided on either side of the main supplementary feeding jet 103. In valve 105 the valve body 108 is provided with a conical seating face 109 urged to open position away from orifice 110 by a light coil spring 111. Diaphragm 112 is mounted in vacuum chamber 113 vented to manifold vacuum through passage 114a (Figure 4) and, during periods of high vacuum, the diaphragm 112 urges the conical seating face 109 to closed position to prevent the flow of supplementary fuel from the chamber 22 into the main metering jet 103. Valve body 114 of valve 104 is provided with a conical seating face 115 urged away from orifice 116 by a pair of springs 117 and 118 of different compressive strengths. The additional spring 118 serves to maintain the valve seating face 115 away from the orifice 116 even though the vacuum chamber 119 acting upon the diaphragm 120 is fairly high, which vacuum, established in the vacuum chamber 119 through the conduit 121 (Figures 3, 4 and 6), would be sufficient to overcome single spring 117. Thus, the valve 104 is open at fairly high intake manifold vacuums, and feeding of supplementary fuel through the orifice 116 and conduit 122 into the main metering jet 103 will be possible even though flow through the orifice 110 of valve 105 and the conduit 123 then through 128 and orifice 129 into the metering jet 103 will be interrupted by seating of face 109 against the action of the spring 111. A metering orifice 124 is provided in the conduit 122 to meter the flow of supplementary fuel into the main jet 103 from the valve 104.

At high manifold vacuum both valves are closed, at low vacuum, such as obtains at full throttle, both valves are open. Inasmuch as orifices 124 and 129 are in series, the larger or full power orifice 129 being placed after the small or part throttle orifice 124, when the full power

valve is closed antidentalont fluid will flow only through the orifice 124.

Thus, it may be seen that the flow of supplementary fuel through the valve 104 will take place under vacuums which are sufficient to close each of the valves 65 and 105. By the employment of the two valves 104 and 105, more accurately metered flow of supplementary fuel to the jet 103 at higher vacuums is possible than by the provision of one such valve, and the flow of fluid may be closely regulated by the adjustment of the tension and the comparative strengths of springs 117 and 118 of valve 104 and the spring 111 of valve 105, by the relative dimensions of the orifices 109 and 115, and by the comparative resistance of diaphragms 120 and 112.

As shown in Figure 3, the main metering jet 103 for the feeding of supplementary fuel into the intake manifold of the engine is similar in construction to the metering jet 53 for main fuel as hereinbefore described. However the metering jet 103 is not open to the float chamber and flow from the float chamber to the venturi does not occur directly as with the main fuel. The main supplementary fuel jet 103 comprises a closed, generally cylindrical casing 124a having an axial, generally cylindrical bore 125 closed at one end by threaded cap 126. The bore 125 also receives an axially apertured threaded cap 127 having a central bore 127a and apertures 128 communicating therewith. A metering jet block 129 is disposed in the bore 125 extending radially thereto and having a central metering jet formed interiorly thereof for the passage of supplementary fuel therethrough. A cylindrical, axially bored sleeve 130 is mounted within the bore 125 beyond the block 129 and is peripherally apertured as at 130a. An air bleed chamber 131 is defined by a dome-like cap 132 apertured to admit air to the chamber which communicates with the interior of sleeve 130 through passages 133 and apertures 130a. Thus, it may be seen that supplementary fuel passing through the conduits 122 and 123 (Figure 6) will flow through the metering jets 129 and 124 into the sleeve 130 and air from chamber 131 will be admixed with the supplementary fuel passing through the sleeve 130 in the manner hereinbefore described.

The present invention also provides means whereby an added amount of supplementary fuel is fed to the main fuel-air stream entering the intake manifold of the engine during rapid acceleration caused by movement of the throttle controls. This additional amount of supplementary fuel is fed through an accelerating pump 134 similar to the pump 86 hereinbefore described in connection with the feeding of main fuel upon acceleration. As shown in Figure 5, the pump 134 is positioned within the housing defined by the sections 28 and 30 formed in the casing sections 12 and 11 respectively.

The pump 134 comprises a pump actuating arm 40 connected through throttle links 38a and 38b to throttle lever 37 as hereinbefore described. The pump 134 is actuated under the same conditions as the pump 86 hereinbefore described for the feeding of main fuel upon acceleration. The pump 134 is provided with a slidble sleeve 135 having a dependent gasket 136 contacting the interior surfaces of the housing 28 and a coil spring 137 urging the sleeve 135 against the end of the actuating rod 40 by bearing against a flange 138 which is mounted on the actuating rod 42. A second coil spring 139 is compressed between the top interior surface of the housing section 30 and 75

against the upper surface of a sleeve 140 contacting the upper surface of the flange 138. Ingress to the pump housing is provided by passage 141 communicating with chamber 22 (Figure 4) and egress is provided through passage 142 communicating with nozzle 96.

The sleeve 140, as best shown in Figure 6, carries an arm 143 extending radially from the actuator arm 40 through a slot 144 formed in housing sections 28 and 30 on that side of the housing adjacent the diaphragm and spring urged valve 104. The arm 143 is formed with a depending portion 145 and a second portion 146 parallel to the arm 143. The free end of portion 146 carries a cylindrical open-ended boss 147 receiving a piston 148 urged downwardly by spring 149.

It may be seen from Figure 6 that, upon sudden acceleration of the engine and the depression of the actuating arm 40 by movement of the throttle lever 37, the piston 148 will come into contact with the upper surface of the valve 104. Upon contact of the piston with the valve, the valve 104 will be depressed to seat the seating face 115 in orifice 116 cutting off the flow of supplementary fuel therethrough. Thus, during rapid acceleration, the feeding of anti-detonant fuel will take place through the metering valve 105 exclusively. Following acceleration and during operation of the engine at high speed, the arm 40 will remain in depressed position to maintain the valve 104 in closed position. As soon as that vacuum necessary to close the valve 105 has been reached, this valve will be closed by the action of the diaphragm 112, while the valve 104 remains mechanically closed by means of the arm piston 145 to prevent the flow of fluid through this valve. This stopping of the flow through both valves at full throttle and high vacuums results in a substantial saving of supplementary fuel inasmuch as it is thus possible to operate the engine at high speed where no detonation takes place without feeding any supplementary fuel to the engine. This permits a more sensitive setting of the valve 104 so that flow may be obtained at lower speeds where knock is more likely to occur without the necessity of feeding unwanted fuel at high speeds.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. A dual carburetor comprising casing means providing an air inlet passageway and a pair of isolated fuel chambers, floats in said chambers, intake valves controlled by said floats for controlling flow of fuel into said chambers from a source, spaced choke and throttle valves in said air passageway, a Venturi throat in said passageway between said valves, metering jets connecting said chambers with the Venturi throat to produce a mixture of air from the choke valve and fuel from the chambers, vacuum-operated valve means regulating flow to one of said jets from one of said chambers to control the content of fluid from said one chamber in said mixture in accordance with manifold pressure of the engine, pump means operated by an opening movement of the throttle valve to feed additional fuel from both chambers to the Venturi throat to provide an additional fuel charge upon rapid acceleration of the engine and means operable

upon movement of said throttle valve to a predetermined open position for decreasing the flow of fuel from said one of said chambers.

2. In a dual carburetor for introducing a main fuel-air mixture containing supplementary fuel into an air intake located centrally of said carburetor, a pair of fuel chambers located on opposing sides of said air intake, one of said fuel chambers being connected to a source of main fuel and the other of said fuel chambers being connected to a source of supplementary fuel, means located in said one float chamber for effecting the introduction of main fuel into said air intake in accordance with the amount of air flowing through said intake, valve means in communication with said one chamber for introducing main fuel into said intake in accordance with manifold vacuum of said engine, pump means in communication with said one chamber for introducing an additional main fuel charge into said air intake when said engine is accelerated, additional valve means located in said other chamber for introducing supplementary fuel to said intake in accordance with intake manifold vacuum of said engine, additional pump means in communication with said other chamber for introducing supplementary fuel into said air intake during rapid acceleration of said engine, and means controlled by said additional pump means for interrupting the flow of supplementary fuel through said additional valve means when said engine is operated at high speed.

3. A dual carburetor comprising a casing defining an air inlet, a throttle valve located in said inlet, a choke valve located in said inlet, a venturi located between said valves, a reservoir for containing a body of main hydrocarbon fuel, means for introducing main fuel from said reservoir into said venturi, a second reservoir located on the other side of said air inlet for containing a body of supplementary fuel, valve means located in said second reservoir for controlling the introduction of supplementary fuel therefrom to said venturi, pump means in communication with said second reservoir for injecting an additional charge of supplementary fuel into said venturi upon movement of said throttle valve, and means actuated by said pump means for engaging said valve means when said throttle is open to prevent feeding of supplementary fuel through the valve means to said venturi during operation of said engine at full throttle and high speed.

4. In a dual carburetor for the introduction of main fuel and supplementary fuel into an internal combustion engine and having an air inlet with a throttle valve located therein, separate reservoirs on either side of said inlet for containing main fuel and supplementary fuel and pressure-controlled valve means located in said supplementary fuel reservoir for injecting supplementary fuel into said intake ahead of said throttle valve in accordance with the manifold pres-

sure of the engine, pump means for injecting an additional charge of supplementary fuel upon sudden acceleration of said engine and means for interrupting the flow of supplementary fuel from said reservoir during operation of the engine at high speeds, said pump means including a pump actuator arm linked to said throttle valve, a pump chamber in communication with said supplementary fuel reservoir, means for confining supplementary fuel in said pump chamber under pressure upon movement of said arm, and a conduit leading from said pump chamber to said inlet for conveying supplementary fuel under pressure from said pump chamber to said inlet upon movement of said arm linked to said throttle valve, and said flow interrupting means including an arm secured to sum pump actuator arm for movement therewith and piston means resiliently mounted on said arm for contacting said pressure-controlled valve means to close the same upon movement of said actuator arm.

5. In a dual carburetor comprising a casing defining an air inlet and an outlet adapted for connection to the intake manifold of an internal combustion engine, a venturi between said inlet and said outlet, a throttle valve between said venturi and said outlet, a plurality of fuel reservoirs supplying different fuel respectively to said venturi, valve means between one of said reservoirs and said venturi controlled by pressure at said outlet for introducing an increasing amount of fuel with increasing manifold pressure, and closure means connected to said throttle valve for closing said valve means when said throttle valve is moved to a predetermined position.

6. In a dual carburetor assembly including a plurality of fuel chambers and a throttle valve, the improvement comprising first and second valves communicating with one of said chambers and vented to the engine intake manifold end of the carburetor, said valves being biased to open position, said first valve closing before said second valve as manifold vacuum increases, said second valve opening before said first valve as manifold vacuum decreases, and closure means connected to said throttle valve for closing said second valve at a predetermined open position of said throttle valve.
